UNITED STATES PATENT OFFICE.

PAUL WENIGMAN, OF CHICAGO, ILLINOIS, ASSIGNOR TO MICHAEL A. McLAUGHLIN, OF SAME PLACE.

ELECTRIC BELT.

SPECIFICATION forming part of Letters Patent No. 650,499, dated May 29, 1900.

Application filed March 14, 1900. Serial No. 8,599. (No model.)

To all whom it may concern:

Be it known that I, PAUL WENIGMAN, a citizen of the United States, residing at Chicago, in the county of Cook and State of Illinois, have invented a certain new and useful Improvement in Electric Belts, (Case No. 1,) of which the following is a full, clear, concise, and exact description.

My invention relates to improvements in electric belts, and has for its object the provision of apparatus wherein the electric current may be more readily applied to the human anatomy as a curative agent.

More specifically my improvements relate to means for establishing better electrical connection between the different portions of the belt, whereby its beneficial effect is increased and the waste of current is diminished, employing in the belt a form of dry-battery cell of such construction as to adapt it particularly to the use named and providing permanent connections and a regulating device in association with the battery whereby the current may be controlled and effectively directed to the part or parts of the body to be treated.

Hitherto electric belts have commonly been constructed of a plurality of small cells adapted to be excited by a liquid electrolyte, the said cells being connected together by means of link couplings. These belts required frequent renewal of the said electrolyte, while the manner of connecting the cells was wasteful of the current in that the resistance of the belt was considerable and short circuits between the battery-cells were frequently established. In the belt of my invention these difficulties are obviated.

The belt herein set forth embodying my invention may be briefly described as consisting of a flexible band or strip of material adapted to encircle the body, upon one side of which are disposed the electrodes, while upon the other side are mounted a plurality of flat dry-battery cells permanently connected together with a regulating device in series with the electrodes and the battery. Connection is established between the said electrodes and the dry-battery cells by means of insulating-cords connecting with terminals provided with a clamping device adapted to

insure electrical continuity between the cords and the electrodes.

My improvements will be more readily understood by reference to the accompanying drawings, illustrating a belt constructed in accordance with my invention, wherein—

Figure 1 is a view of the exterior or outer side of the belt. Fig. 2 shows in perspective one of the electrodes provided with a clamp for the conducting-cord. Fig. 3 is an exterior view of one of the battery-cells. Fig. 4 is a plan view of the two longitudinally-separable parts of said cell. Fig. 5 is a transverse sectional view of the cell, the parts of the cell being shown slightly separated therein; and Fig. 6 is an enlarged view of the belt, regulating device, and battery-cells.

Similar parts in each of the several figures are designated by the same letters of reference.

In Fig. 1 I have illustrated a belt equipped with six battery-cells, which number, however, may be varied as desired, ranging ordinarily from six to twelve. These cells are connected in series, the same being mounted upon a strip *a* of canvas or leather, which is provided with a permanent inner cover *b*, preferably of chamois, and a removable apron *c*, adapted normally to cover the battery-cells. Upon the right is disposed a rheostat *d*, having a movable arm *d'*, adapted to travel over fixed metallic contacts *d''*, mounted upon an insulating-base and electrically connected by means of a strip of graphite or other suitable resistance material. A silk-covered insulating-cord *e* is provided with a flat terminal hook *e'*, adapted to be secured beneath a washer upon the rheostat and establish electrical connection with the battery-cells. Connected with the conducting-cord are hooks *e'' e'''*, which are respectively adapted to be snapped into holes upon the spring-straps *f' f''*, soldered or otherwise secured to the metallic electrodes *ff'*. These straps are formed of spring-like material, having an opening cut in one end, through which the other end is adapted to be slipped, in which position the terminal hook *e''* of the conducting-cord is snapped through the opening in the inserted end. The tension of the spring metal therefore clamps the terminal hook in excellent

electrical contact with the strap and electrode. Upon the left of the row of battery-cells is provided a small flat binding-post *g*, which is adapted to receive one terminal of 5 a second conducting-cord *g'*, which extends to the negative electrode *h* of the battery. It will be understood that by means of these conducting-cords any suitable means for applying the electrical current to different parts 10 of the body may be placed in electrical connection with the battery-cells. I have chosen, however, to illustrate my invention in connection with the metallic disks *f h*, which are most commonly employed. These, if desired, 15 may be covered with chamois or other material suitable for applying current to the body. The cases *i* of the battery-cells *k* are molded from hard rubber, vulcanite, or other suitable material, so that the two halves fit accurately 20 together.

At or near the bottom of the upper half *i'* of the casing is secured the zinc element *k'*, while the carbon element *k''* is similarly disposed in the lower half *i''* of the casing. Connection is established with said elements by 25 means of screws, which respectively extend through lugs *k³ k⁴* in the top and bottom walls of the casing. A V-shaped peripheral rib *i²* is provided upon the lower half of the casing, 30 which accurately fits into a corresponding groove provided in the upper casing, serving to seal the contents of the cell, paraffin or a suitable cement being placed in said groove to make the joint air-tight.

35 After the interior space in the cell has been filled with any suitable dry-battery paste, such as is well known in the art, the screws *i³* are inserted, which serve to clamp the top and bottom portions of the casing *i* together. The 40 completed battery-cells are then riveted upon the supporting fabric of the belt, as shown in Fig. 6. Connection between the separate cells is established by means of short lengths of flexible conducting-cord *l*, which are placed 45 beneath the rivets upon the opposite side of the belt, uniting the positive and negative terminals or lugs of each of the battery-cells, as shown in dotted lines in Fig. 6. These connecting rivets and cords are disposed 50 within the belt between the supporting fabric and the chamois covering *b*, avoiding any opportunity for short-circuiting the belt upon its inner side.

The strap *m*, of elastic webbing, is provided 55 with terminal hooks *m'*, adapted to engage rings *m²*, mounted at or near the ends of the belt proper. The strap serves to hold the belt in place about the wearer.

From the manner of connecting the battery-cells and the associated parts upon the belt it will be seen that the continuity of all the electrical connections is insured, while the resistance of the belt is very low. By means of the rheostat *d* the strength of the 60 current may be regulated and controlled by the wearer, as desired.

The employment of dry-battery cells ob-

viates the necessity of renewing the electrolyte, said cells serving to supply current for many months without the necessity of attention on the part of the patient. They are also readily renewed, since by simply removing the top screws *i⁴* in the lugs *k³* it will be seen that the upper half of each of the battery-casings may be removed to permit of renewing the dry-battery paste. This, it will be seen, can be accomplished without disturbing the permanent connections of the cells upon the belt and involves merely the removal of a single screw for each of the cells 80 thus renewed.

The form of battery-cell is peculiarly adapted for the use in question, since it is strong, compact, and light, thus placing no inconvenience upon the wearer of the belt.

A relatively-large surface of the carbon and zinc elements is exposed in the cells to the action of the dry-battery compound, and the voltage of the cells remains quite uniform.

Having now described an electric belt constructed in accordance with my invention, I claim as new, together with all such modifications as may be made by mere skill or are by law implied, the following:

1. In an electric belt, the combination with a plurality of battery-cells, of a plurality of flexible conductors disposed within the interior of the belt, rivets passing through the body of the belt and securely uniting the terminals of the battery-cells with the flexible conductors, whereby the said cells are permanently connected together and the resistance of the belt is minimized, and electrodes connected with the battery, adapted to be applied to the parts of the body to be treated, substantially as described.

2. In an electric belt, the combination with a plurality of battery-cells, of a plurality of flexible conducting-cords *l* disposed within the interior of the belt, a plurality of rivets permanently uniting the terminals of the battery-cells and the conducting-cords each to each with the body of the belt, whereby the electrical resistance of the belt is minimized and short-circuiting is avoided, and electrodes connected with the battery, adapted to be applied to the parts of the body to be treated, substantially as described.

3. In an electric belt, the combination with a plurality of battery-cells, of a plurality of flexible conducting-cords *l* disposed within the interior of the belt, a plurality of rivets permanently uniting the terminals of the battery-cells and the conducting-cords each to each with the body of the belt, whereby the electrical resistance of the belt is minimized and short-circuiting is avoided, a plurality of removable screws *i⁴* uniting the permanently-connected terminals of the battery-cells with the respective elements thereof, and electrodes connected with the battery, adapted to be applied to the parts of the body to be treated, substantially as described.

4. The combination with a terminal part or electrode f , of a strap f' of spring-like material connected with the said electrode and having an opening in one end through which the other end of said strap is adapted to be slipped under tension, and a receptacle or aperture provided in the latter end, adapted to receive an electrical conductor, wherein said conductor is clamped by the tension of 10 said strap, substantially as described.

5. The combination with an electrode for electric belts, of a combined supporting-strap and clamping part f' formed of spring-like material, the ends thereof being overlapped and provided with a receptacle for an electrical conductor, wherein said conductor is clamped by the tension of the strap, substantially as described.

6. The herein-described dry-battery cell adapted for use in electric belts, comprising a flattened casing formed of two longitudinally-separable parts or receptacles of insulating material, respectively provided with the two elements of the cell, terminals respectively connected with said elements, extending from the opposite side walls of the casing, and means for sealing and securing together the parts of said cell, substantially as described.

7. In a battery-cell of the class described, the combination with a casing of insulating material formed of two longitudinally-separable parts, a carbon and a zinc element respectively disposed in said parts, terminals respectively connected with said elements and leading from the opposite side walls of the casing, and means for clamping the separable parts of said cell together, substantially as described.

8. In a miniature battery-cell, the combination with two longitudinally-separable casings or receptacles adapted to fit tightly together, said separable receptacles respectively carrying two electrodes or elements in juxtaposition to each other, terminals connecting with said elements, and means for securing the receptacles closely together, substantially as described.

9. In a battery-cell of the class described,

the combination with two receptacles of insulating material fitting closely together, of two elements respectively disposed in juxtaposition to each other upon the opposite interior walls of said receptacles, terminals upon the opposite sides of the cell, respectively connected with the elements upon the interior, and means for clamping the separable parts of the cell together, substantially as described.

10. The combination, in a miniature battery-cell for use with electric belts, with two flattened receptacles of insulating material, having overlapping engaging faces, of a carbon and a zinc element respectively disposed upon the side walls of said receptacles, terminals disposed upon the exterior of said receptacles and connected through their side walls with the elements, and screws passing through the said receptacles adapted to secure them together, substantially as described.

11. In a miniature dry-battery cell adapted for use upon electric belts, the combination with separable paired casings i i' of insulating material, having engaging faces provided with recessed or overlapping edges, of a zinc and a carbon element respectively disposed opposite each other within the said casings upon their flattened walls, terminals k^3 k^4 upon the exteriors of said walls and respectively connected with the said electrodes, and screws i^3 adapted to secure the separable casings tightly together, substantially as described.

12. The combination with a terminal part or electrode f , of a strap f' of resilient material connected with the said electrode, the ends of said strap being overlapped under the tension of said material, whereby a receptacle for an electric conductor is formed, wherein said conductor is adapted to be securely clamped, substantially as described.

In witness whereof I hereunto subscribe my name this 9th day of March, A. D. 1900.

PAUL WENIGMAN.
